Primary Examiner — Ricky Pham(74) *Attorney, Agent, or Firm* — Gardner, Linn, Burkhardt & Ondersma LLP(57) **CLAIM**

The ornamental design for a vegetable cutter blade, as shown and described.

DESCRIPTION

FIG. 1 is a perspective view of a vegetable cutter blade showing my new design;

FIG. 2 is a top plan view thereof;

FIG. 3 is a bottom plan view thereof;

FIG. 4 is a front elevation thereof;

FIG. 5 is a rear elevation thereof; and,

FIG. 6 is a side elevation thereof; the opposite side being identical.
